Primary Examiner — T Chase Nelson*Assistant Examiner* — Jeff Lenard D Torres**(57) CLAIM**

The ornamental design for a girdle, as shown and described.

DESCRIPTION

FIG. 1 is a top perspective view of a girdle design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom side view thereof; and,

FIG. 8 is a front view thereof showing flaps of the girdle open.

The broken lines in the figures show portions of the girdle that form no part of the claimed design.
